(57) **CLAIM**

The ornamental design for an electrical cable connector as shown and described.

DESCRIPTION

FIG. 1 is a top, front, right perspective view of an electrical cable connector of our design;

FIG. 2 is a bottom, rear, left perspective view thereof;

FIG. 3 is a front, top, right perspective view thereof;

FIG. 4 is an enlarged front, top, right perspective view of a portion thereof, as indicated at region FIG. 4 of FIG. 3;

FIG. 5 is a bottom, rear, left perspective view thereof;

FIG. 6 is an enlarged bottom, rear, left perspective view of a portion thereof, as indicated at region FIG. 6 of FIG. 5;

FIG. 7 is a front elevation view thereof;

FIG. 8 is a rear elevation view thereof;

FIG. 9 is a left side elevation view thereof;

FIG. 10 is a right side elevation view thereof;

FIG. 11 is a top plan view thereof; and,

FIG. 12 is a bottom plan view thereof.

The even length broken lines in the drawings depict portion of the electrical cable connector that form no part of the claimed design. The dash-dot-dash broken lines in the drawings depict the boundaries of enlarged views and form no part of the claimed design.
